COMBINED PHONOGRAPH AND RADIO OR SIMILAR ARTICLE

Lawrence Levow, Huntington, N.Y., assignor to Harmon-Kardon, Incorporated, Plainview, N.Y., a corporation of Delaware

Filed Jan. 8, 1969, Ser. No. 15,261

Term of patent 14 years

Int. Cl. D14—01

U.S. Cl. D56—4

FIG. 2.

FIG. 1 is a front, top and left side perspective view of a combined phonograph and radio or similar article showing my new design.

FIG. 2 is a front and top perspective view thereof.

The back and bottom are essentially plain and unornamented.

The dominant features of my new design are shown in solid lines in the drawings, the fragmentary broken line showing of a representative phonograph turntable being for illustrative purposes only.

I claim:

The ornamental design for a combined phonograph and radio or similar article, as shown and described.
